(57) **CLAIM**

The ornamental design for a motor shell, as shown and described.

DESCRIPTION

FIG. 1 is a perspective view of a motor shell showing our new design.

FIG. 2 is a front elevational view of the motor shell; the rear elevational view, left side, and right side being a mirror image.

FIG. 3 is a top plan view of the motor shell.

FIG. 4 is a bottom plan view of the motor shell; and,

FIG. 5 is a cross-sectional view of the motor shell, taken along line 5-5 of FIG. 2.
